(57) **CLAIM**

We claim the ornamental design for a tee pipe coupling, as shown and described.

DESCRIPTION

FIG. 1 is a front, right, perspective view of a tee pipe coupling showing our new design;

FIG. 2 is a front elevational view thereof, the rear elevational view being identical thereto;

FIG. 3 is a right side elevational view thereof;

FIG. 4 is a left side elevational view thereof;

FIG. 5 is a top plan view thereof; and,

FIG. 6 is a bottom plan view thereof.

In the drawings, the broken line showing is to illustrate portions of the article and form no part of the claimed design.
